UNITED STATES PATENT OFFICE.

ROBERT L. HORSLEY, OF FORT WORTH, TEXAS, ASSIGNOR TO WORTH WIRE WORKS, OF FORT WORTH, TEXAS, A CORPORATION OF TEXAS.

MAT.

SPECIFICATION forming part of Letters Patent No. 784,564, dated March 14, 1905.

Application filed May 31, 1904. Serial No. 210,387.

To all whom it may concern:

Be it known that I, ROBERT L. HORSLEY, a citizen of the United States, residing at Fort Worth, Texas, have invented certain new and useful Improvements in Mats, of which the following is a specification.

This invention relates to an article of manufacture; and the object is to manufacture mats for various purposes—such as door-mats, mats for aisles of churches or other buildings, mats for soda-fountains, mats for bar-counters—and to construct mats which are flexible and easily rolled up for convenience in moving and cleaning and which will retain their shape permanently and not buckle.

Other objects and advantages will be fully explained in the following description, and the invention will be more particularly pointed out in the claims.

Reference is had to the accompanying drawings, which form a part of this application and specification.

Figure 1 is a broken plan view of a mat, illustrating in detail the manner of constructing the mat. Fig. 2 is an end view of a spring-wire coil, illustrating the style of coil preferably used in making mats.

Similar characters of reference are used to indicate the same parts throughout both views.

This improved mat has a cable A, which extends about the four sides of the mat or about the two sides and the ends of the mat. This cable is flexible. It is made of a core B of some suitable material and a wire wrapping E. The cable A is constructed by suitable machinery and the wire wrapping is spaced slightly between the coils. The cable is flexible, but not elastic, and longitudinally considered it is incompressible. The spacing of the wrapping slightly apart renders the cable flexible. The cable A may be said to be the "frame" of the mat. The mat is provided with a rod D, placed in each end of the mat. The mat is completed with the cable A, the rods D, and the woven wire. The coil 1 engages the cable A and the rod D and also the coil 2 in the manner shown. The coil 2

engages the rod D, the coil 1, and the coil 3. 50 The coil 3 engages the coil 2 and the coil 4. Coil 4 engages coil 3 and coil 5. The mat may be made of any suitable length and width. The opposite end of the mat is completed in the same manner as was commenced. 55 The rod D makes the ends of the mat reasonably rigid, and the sides of the mat are flexible. The rod D is loosely mounted in the position shown and not secured by any fastening device other than the coils of wire and 60 the cable A. The cable A prevents the rod D from sliding out at the sides of the mat. The coils of wire are united or looped at the sides of the mat in such a manner as to leave the sides of the mat flexible. Coils 2 and 3. 65 are united at their ends in the following manner: The coil 2 is bent or extends under the cable A and a loop is formed at 6 and the end of the coil 2 is bent back over the cable A. The coil 3 extends over the cable A and 70 through the loop 6 of coil 2 and stops at 7 on the inside of the cable A, thus forming a hinge-like joint with the coil 2 at the point 6. In the same manner the coil 4 after leaving the coil 3 is bent under the cable A and a 75 loop formed at 8, and the coil 4 is then bent back to a point inside of the cable A. The coil 5 after engaging the coil 6 is bent over the cable A and engages the loop 8 of coil 4 and is then bent back under the cable A to 80 the inside of said cable. Thus the coils 4 and 5 form a flexible or hinged joint at 8 and the ends of the wire are disposed of with a neat finish. In this manner all the coils of the mat are to be attached to the mat. As the 85 cable A is flexible and the juncture of each pair of coils is looped or pivotally connected together, the sides of the mat are left free to be rolled up or bent.

There is an advantage in constructing the 90 mat with flattened spring-wire coils. When the mat is bent or rolled, the coils will change positions relative to each other slightly, and thus break loose any dirt that may be clinging to the coil. The wire-spring coil will 95 form a cushion for the feet, and about saloon-counters and soda-water fountains the coils will hold the feet up out of the water or other

liquid which usually falls to the floors in such places. The coils all engage the cable loosely, and yet the coils maintain their positions on the cable permanently, and after a 5 mat is unrolled it will assume a flat shape or shape conforming to the surface on which it is placed. The cable and the coils will always return to their normal and proper positions relative to each other without any 10 buckling whatever.

Having fully described my invention, what I claim as new, and desire to secure by Letters Patent, is—

1. As a new article of manufacture, a flexible mat constructed of a cable and coils of spring-wire engaging said cable and forming loops pivoted together on the outside of said cable.

2. As a new article of manufacture, a mat 20 constructed of flexible cable forming the frame of the mat, coils of wire woven together and having their ends looped about said cable at the sides of the mat, and each pair of coils having their ends pivoted to-

gether outside of said cable and rods loosely 25 mounted in the ends of the mat for forming rigid ends of the mat.

3. As a new article of manufacture, a non-elastic mat composed of a frame consisting of a flexible and non-elastic cable, and coils 30 of spring-wire woven together, and each pair of wire springs having their ends pivotally connected together about said cable.

4. As a new article of manufacture, a mat composed of a non-elastic flexible cable 35 forming a frame for the mat and a series of coils of spring-wire flexibly woven together in series and each pair of wire springs having their ends flexibly connected together on the outside of the frame.

In testimony whereof I set my hand, in the presence of two witnesses, this 25th day of May, 1904.

ROBERT L. HORSLEY.
